FEED OR DRAWING ROLLER FOR TEXTILE MACHINES

Joseph Fossel, Grafton, Mass.

Application March 7, 1933, Serial No. 659,944

4 Claims. (Cl. 19—141)

The present invention relates to a feed or drawing roller for textile machines and particularly to a roller for spinning machines and for machines for preparing fibrous material for spinning, such as draw boxes, combing machines and lap machines.

In prior devices of this character, the feed or drawing instrumentalities have been in general of two different types; one type involves intermeshing fluted rollers between which the fibrous material is fed or drawn, and the other type involves a fluted roller which engages a cylindrical roller having a smooth surface. In the first type, the intermeshing rollers provide an uneven tension or draft on the sliver or ribbon which results in an uneven web of material, leaving weak places in the finished filament. The intermeshing rollers also have a tendency to crush the fibers as they are passed therebetween, and it is practically impossible to form a uniform web or ribbon of material without weak or thin places by the use of intermeshing rollers.

In the use of a fluted roller in connection with a roller having a cylindrical surface, it has been customary to form the feed or drawing roller with a relatively large number of closely arranged teeth which present relatively sharp edges for engagement with the pressure roller. In order to procure a positive feed or drawing of the fibers between a roller of this character and the pressure roller, it has been necessary to provide an extremely heavy pressure between said rollers with the result that the fibers passing between the rollers are crushed or broken and with the further result that the outer covering of the pressure roller is subjected to undue wear, particularly in the formation of corrugations therein by the action of the feed roller.

To avoid the formation of grooves in the pressure roller by the action of the teeth or ribs of the feed roller, it has been the practice to vary materially the spacing between successive teeth of the roller. Although this eliminates the formation of grooves in the pressure roller, it results in an uneven feeding or drawing action which prevents the formation of a uniform web of material. In other prior art devices, the width of the outer surfaces of successive teeth or ribs is varied materially; this also results in an uneven feeding action which produces an uneven web. It is the principal object of the present invention to overcome the objections of the prior devices by a feed roller which operates in conjunction with a pressure roller having a cylindrical surface, the feed roller providing for a

positive and uniform feeding or drawing action on the fibrous material.

In previously known feeding or drafting instrumentalities, it has been difficult to maintain a uniform width of ribbon or sliver as it passes between the feed roller and the pressure roller, since, in the usual type of feed rollers, the fibrous material is inclined to flare as it passes between successive pairs of rollers and beyond the rollers. The spreading action has been overcome by guides which maintain a uniform width of ribbon or web although, as a result of the action of the guides, the opposite edges of the ribbon become somewhat thicker than the central portion thereof, and the rollers, between which the web thereafter passes, cannot obtain a positive engagement with the web over the entire width and cannot, therefore, provide a uniform and positive feeding or drawing action on the web. A further object of the present invention resides in the provision of a feed roller which, by its positive and uniform engagement with the web of material, prevents flaring thereof as it is fed between said feed roller and the pressure roller.

Long drafting of fibrous material, particularly cotton, prior to the present invention, has been impossible, by reason of the uncertain or non-uniform engagement between the feed roller and the cooperating pressure roller, in a drawing frame or other machine for preparing the material for spinning which is adapted for the short drafting of fibrous material. A further object of the present invention is accordingly to provide a feed roller which is suitable for both short drafting and long drafting of cotton or other fibrous material and which, in use will deliver a uniform web from the machine.

Other and further objects and advantages of the invention will appear from the following description taken in connection with the accompanying drawings in which:

Fig. 1 is a vertical sectional view through a drawing frame showing an application of a roller embodying the present invention.

Fig. 2 is an enlarged fragmentary vertical section showing the operation of a roller embodying the present invention.

Like reference characters refer to like parts in the different figures.

Referring first to Fig. 1, the novel feed roller is shown in connection with a draw box of the usual construction and the particular draw box shown is arranged for the long drafting of cotton fibers. The web or sliver 1 passes successively between the positively driven feed rollers 2, 2a and 2b, and

the cooperating pressure feed rollers 3, 3a and 3b with said pressure rollers held in engagement with the corresponding feed roller with a predetermined pressure through suitable weights or springs suspended from or attached to members 4 on the shafts of the pressure rollers. The web 1 is drawn or elongated materially by each successive pair of rollers so that the web as it leaves the roller 2b is materially longer and lighter in weight than the web as it passes between the rollers 2 and 3. The attenuation of the web by a draw box incorporating the novel rollers is as much as thirteen or fourteen times the original length of the web, and the operation of the feed rollers permits the attenuated web to be entirely uniform throughout.

15 Each successive feed or drawing roller is driven at a faster rate than the preceding roller to accommodate the increasing length of the sliver as well as to procure a further drawing operation, by suitable gearing shown in dot-dash lines in Fig. 1. Referring to these figures, a drive shaft 5 below the second feed roller 2a carries a gear 6 which engages an idler gear 7, the latter meshing with a gear 8 on one end of the feed roller 2 for actuating said roller. The drive shaft 5 also carries a larger gear 9 which drives a gear 10 on the third feed roller 2b through idler gears 11 and 12 on a single shaft, said gears meshing respectively with the gears 9 and 10. The second or middle feed roller 2a is driven from a gear 13 on the feed roller 2b through an idler gear 14 which meshes with a gear 15 on the roller 2a. A pair of cooperating rollers 18 which maintain a desired tension on the web as it comes from the drawing rollers, said rollers 18 operating to draw the sliver through a trumpet 20 positioned adjacent the third roller 2b, are driven from the drive shaft 5 at the proper speed by a gear 16 which meshes with a gear 17 on one of the rollers 18 and with the gear 13.

40 In order to obtain a uniform elongation of the web or sliver between successive feed rollers, it is necessary that the web be given a positive and uniform feeding action by each roller and to this end the feed rollers 2, 2a and 2b are of a novel construction best shown in Fig. 2. According to 45 the invention, each feed roller is in the form of a cylinder, the outer surface of which is provided with a plurality of relatively large teeth or ribs 21, said ribs being materially reduced in number from the usual number of ribs provided in prior art 50 machines. Each rib 21 provides an outer land or surface 22 concentric to the axis of the roller and of a material width to provide a cylindrical surface on each rib for engagement with the cooperating pressure roller. The opposite faces 23 of 55 each rib extend at an angle of substantially 45° to each other and also extend at equal angles to the outer surface 22 of the rib. The outer surfaces 22 of successive ribs vary slightly in width from a minimum width of approximately one 60 sixty-fourth of an inch, the variations being on the order of from two to seven thousandths of an inch in order to avoid the formation of permanent notches or depressions in the surface of the pressure roller by continued use of said pressure roller. 65 It will be apparent that if all of the ribs were of equal width, they would soon form uniformly spaced depressions in the surface of the pressure roller and the latter would then function as a gear meshing with the teeth or ribs of the feed roller, a result which is obviously objectionable and undesirable. The small variations in widths in successive ribs provided by the present invention are great enough to avoid a permanent notching 70 of the pressure rollers so that the latter are

usable over a relatively long period of time before it is necessary to replace them; at the same time, the variations in width of successive ribs are so slight that the varying feeding effect produced on the sliver or web cannot be noticed regardless of the extent to which the web is drafted or attenuated in the draw box.

75 With drawing rollers of the type shown in Fig. 2, and with each successive roller operating at a faster rate than the preceding roller, it will be apparent that the web or sliver is positively and uniformly fed through each successive pair of rollers and at the same time each feed roller positively supports the fibers against being pulled through by the successive feed roller so that each fiber in the web is advanced relative to each other fiber the same predetermined amount and a uniform web greatly attenuated is delivered from the draw box. The use of this type of feed roller makes possible a longer draft or greater elongation of the web or sliver as it passes through the draw box than in the prior constructions and at the same time provides for a uniform attenuation by reason of the positive engagement between the surfaces of the feed roller and the corresponding pressure roller.

80 As above stated, the rollers have a relatively small number of ribs which, however, vary somewhat depending on the quantity of material being drawn through the draw box. In the embodiment shown, the first drawing roller 2, which, for most satisfactory operation, is substantially one and one-half inches in diameter, is provided with forty-two ribs and the second drawing roller which operates on a sliver of lighter weight is one and one-fourth inches in diameter with forty-two ribs so that said ribs are thus more closely arranged. The third drawing roller 2b is equal in size to the roller 2 being one and one-half inches in diameter and to accommodate a finer 85 or lighter sliver has sixty ribs, thus providing a closer spacing of the ribs than in either of the preceding rollers.

90 By the formation of each of the ribs with flats or lands 22, with successive lands varying slightly in width from the minimum of one sixty-fourth of an inch, it has been found possible to obtain a positive feeding action by rollers of this type, to materially decrease the pressure exerted on the web or sliver by the pressure roller, and at 95 the same time, to increase the weight of material passing between the cooperating rollers. At the same time the flutes between the teeth or ribs in each roller are preferably all uniform in width. The particular angle of the side surfaces of the ribs and the proper spacing of the ribs in a roller embodying the present invention provide for a definite clamping or engagement of the web or sliver between said roller and the pressure roller which definitely supports each individual fiber in the web against undesired movement and obtains the above-noted result, namely, that each fiber is advanced a predetermined amount relative to each other fiber in the web. This positive gripping action of the ribs of the feed roller also prevents the objectionable flaring or spreading of the web and maintains perfect selvedges at opposite edges thereof. It has been found that the width of the web in passing through a draw box incorporating the novel rollers is maintained entirely uniform throughout the length of the draw box. By eliminating the heretofore necessary guides, the amount of waste commonly known as "fly" resulting from the drawing action is materially reduced.

In the proper drawing of the web, the successive feed rollers are spaced apart a distance slightly greater than the length of the longest fibers in the web so that no fiber is engaged by a 5 succeeding roller until it has been released from the preceding roller. This eliminates breaking of the fibers and also a tendency of the fibers to become disarranged and no longer retain their proper direction in the web.

10 Referring now particularly to Fig. 2, it will be noted that the pressure rollers cooperating with the feed rollers are provided with a layer of felt 24 covered by leather 25 or other resilient material. By this arrangement which, in itself, is 15 not novel, the fluted feed rollers are able to form temporary depressions in the pressure roller during the passage of the web therebetween, so that the feed roller engages the web over a predetermined distance on both sides of the center line 20 of the feed and pressure rollers. The clamping action by each successive pair of rollers is not immediately released but as the material passes therethrough, the clamping action is gradually diminished, providing for a more uniform drawing 25 action between successive pairs of rollers as will be apparent. As most clearly shown in Fig. 2, the spacing of the ribs on the rollers is such that the web is positively engaged at all times by at least two of the ribs and at the same time the 30 spacing and the width of the flats on the ribs is such that a positive clamping action on the web is obtained without the use of excessive pressure between the pressure roller and the corresponding feed roller.

35 It has been found that when the angularity of the opposite surfaces 23 of each of the ribs of the roller is increased so that said surfaces extend at an angle of approximately 50° or more to each other, the clamping action obtainable between 40 said feeding roller and the cooperating pressure roller is decreased so that an increase in the pressure exerted by the pressure roller is necessary to obtain a positive feeding action. At the same time, when the opposite surfaces of each of the 45 ribs extend at an angle of approximately 40° or less to each other, the corners of the ribs between the surfaces 22 and 23 have a tendency to crush or cut the fibers in the web so that the web is damaged and the feeding action is no longer 50 positive and uniform.

55 From the foregoing, it will be apparent that the present invention resides mainly in the provision of a drawing or feed roller for use in spinning machines and in machines for preparing fibrous material for spinning, said roller having a relatively small number of large ribs on the periphery thereof with each of said flutes providing an outer surface concentric to the axis of the roller. The outer surfaces of each of said 60 ribs is of a substantial width and, although the width of successive ribs varies slightly, the variation is so small as to have no effect on the uniform feeding action of the rollers. The opposite faces of each of the flutes extend at an angle of approximately 45° to each other and also symmetrically to the axis of the roller. The invention further resides in the combination of a feed or drawing roller of this type with a cooperating member or pressure roller which provides a 65 smooth, arcuate or cylindrical surface for engagement with the outer surfaces of the ribs, thereby providing a positive feeding action of

the fibers in the web as it passes between said rollers.

70 Although the description has been directed to the function of the drawing roller in connection with a draw box or drawing frame, it will be noted that the use of such a roller is not limited to draw boxes but is applicable as well to combers, ribbon and sliver lap machines, spinning frames and other machines for spinning materials, or for preparing materials for spinning.

I claim,

1. A drawing or feeding roller for use in textile machines, said roller having a small number of relatively large ribs spaced substantially evenly about the periphery of said roller, each of said ribs providing an outer surface of substantial width concentric to the axis of the roller, said outer surfaces being all substantially uniform in width but varying slightly on the order of from approximately two to seven thousandths of an 15 inch from an approximate minimum of one sixtieth of an inch, with the opposite faces of said width extending at an angle of substantially forty-five degrees to each other.

2. In a machine of the class described, the 20 combination with a cylindrical roller presenting a continuous outer surface, of a feed or drawing roller in parallel alignment therewith, said feed roller having a small number of relatively large ribs spaced substantially evenly about the periphery of said roller, each of said ribs providing an outer surface of substantial width concentric to the axis of the roller for engagement with the outer surface of said cylindrical roller, with the 25 opposite faces of each rib extending at an angle 30 of substantially forty-five degrees to each other, said outer surfaces varying slightly in width on the order of approximately two to seven thousandths of an inch from a minimum of one sixtieth of an inch, said feed roller being positively 35 driven for feeding fibrous material between said roller and the cooperating cylindrical roller.

3. In a machine of the class described the combination with a member providing a smooth annular surface, of a feed or drawing roller in parallel alignment therewith, said feed roller having a small number of relatively large ribs spaced substantially evenly about the periphery of said roller, each of said ribs providing an outer surface of substantial width concentric to the axis 45 of the roller for engagement with the arcuate surface of said member, said outer surfaces being all substantially uniform in width but varying slightly on the order of approximately two to seven thousandths of an inch from an approximate 50 minimum of one sixtieth of an inch, with the opposite faces of each rib extending at an angle of forty-five degrees to each other.

4. A drawing or feeding roller for use in textile machines, said roller having a small number 55 of relatively large ribs spaced substantially evenly about the periphery of said roller, each of said ribs providing an outer surface of substantial width concentric to the axis of the roller, said outer surfaces being all substantially equal in width but varying slightly from an approximate 60 minimum of one sixtieth of an inch with the opposite faces of said ribs extending at an angle of substantially forty-five degrees to each other.

JOSEPH FOSSEL.
